UNITED STATES PATENT OFFICE

163,150

COUNTERPOISE HOUSING FOR A DRAFTING MACHINE

Francis E. Vaughan, Pasadena, Calif.

Application November 8, 1950, Serial No. 12,913

Term of patent 14 years

(Cl. D52—1)

To all whom it may concern:

Be it known that I, Francis E. Vaughan, a citizen of the United States, residing at Pasadena, in the county of Los Angeles and State of California, have invented a new, original, and ornamental Design for a Counterpoise Housing for a Drafting Machine, of which the following is a specification, reference being had to the accompanying drawing, forming part thereof.

Fig. 1 is a plan view of a counterpoise housing for a drafting machine, showing my new design; and

Fig. 2 is a front elevation of the design shown in Fig. 1.

I claim:

The ornamental design for a counterpoise housing for a drafting machine, substantially as shown.

FRANCIS E. VAUGHAN.
